UNITED STATES PATENT OFFICE.

CHARLES O. FOEDISCH AND ROY J. FOEDISCH, OF CHICAGO, ILLINOIS.

MAGAZINE FOR PHONOGRAPH NEEDLES.

Application filed November 28, 1921. Serial No. 518,201.

To all whom it may concern:

Be it known that we, CHARLES O. FOEDISCH and Roy J. FOEDISCH, both citizens of the United States, and residents of Chicago, 5 in the county of Cook and State of Illinois, have invented certain new and useful Improvements in Magazines for Phonograph Needles, of which the following is a full, clear, and exact description.

10 The invention relates to devices for holding phonograph needles and for facilitating their placement into the needle socket of a reproducer.

In handling loose needles, it frequently 15 occurs that the sharp point pricks the fingers used to grasp the needle and place it into the needle socket of the reproducer. It also occurs that the points of needles are injured when they are kept loosely in a 20 compartment.

The object of the invention is to provide a simple device which is adapted to hold a supply of needles with their points protected against injury and against all danger 25 of pricking the fingers while their shanks are exposed and free to be inserted into the needle socket before they are removed from the holder. By this means, it becomes possible to place a needle into the socket without 30 touching the needle point and so that there will be no danger of injury to the fingers or to the needle.

The invention consists in the several novel features hereinafter set forth and more particularly defined by claims at the conclusion 35 hereof.

In the drawings: Fig. 1 is a perspective of a needle holder embodying the invention and a reproducer in position to receive a 40 needle from the holder. Fig. 2 is a detail face view of the holder, one of its sides being broken away. Fig. 3 is a section on line 3—3 of Fig. 2. Fig. 4 is a view of a portion of the periphery or margin of the 45 holder. Fig. 5 is a face view with one side broken away of a device embodying a modified form of the invention. Fig. 6 is a section taken on line 6—6 of Fig. 5. Fig. 7 is a view of a portion of the margin of the 50 holder shown in Figs. 5 and 6.

The improved holder is preferably disk-like in general form and is adapted to receive and retain in its margins a series of phonograph needles in spaced relation so 55 that the shanks will project therefrom so that any one of them may be inserted into

the needle socket 8 of a reproducer 9 without displacing the needle from the holder. In the exemplification of the invention illustrated in Figs. 1 to 4, the holder consists of 60 a pair of sheet metal circular disks 10 which are secured together centrally by a hollow rivet 11 and are spaced apart at their margins to receive a ring 12 between them. Ring 12 is also formed of sheet metal and 65 is formed with radial seats or grooves 13 separated from one another each adapted to receive and frictionally hold a phonograph needle 14. The ring 12 is formed so that it is sufficiently resilient to frictionally 70 engage the needles and hold them against the inner face of one of the disks 10. The ring is sufficiently resilient to frictionally engage needles 14 of different sizes so that 75 loud, soft and medium needles may all be held in thereby. The recesses 13 form pockets which hold the needles spaced from one another so that there will be sufficient space between each needle and its adjacent needles to permit it to be inserted into the 80 socket 8 without interference from the adjacent needles.

A cushion ring 15 is placed between the disks 10 and inwardly of the groove ring 12. This cushion is preferably formed of material, such as cork, which is adapted to be 85 penetrated by the points of the needles 14 without injury to them. This cushion protects the needle points and assists in frictionally holding the needles in the holder. 90

The device is adapted to retain a considerable supply of needles. It can be cheaply produced so that if desired the needle manufacturer may furnish the needles in the 95 holders.

The device exemplifies a holder which is adapted to receive a series of phonograph needles and hold them frictionally in spaced relation with the needle shanks projecting from the margin thereof so that it may be 100 conveniently inserted into a needle socket without handling the needle with the fingers.

In the exemplification of the invention shown in Figs. 5, 6 and 7, the circular ring 105 12 is dispensed with and, in lieu thereof, the disks 10^a are shaped to form pockets 10^b at their marginal portions which are adapted to receive and frictionally retain the needles in spaced relation as heretofore described. 110 A cushion ring 15 of cork or other suitable material is used to protect the needle

points and assist the disks in frictionally holding the needles.

The invention is not to be understood as restricted to the details set forth, since these may be modified within the scope of the appended claims, without departing from the spirit and scope of the invention.

Having thus described the invention what we claim as new and desire to secure by Letters Patent, is:

1. A holder of the character described comprising in combination a cushion in the holder penetrable by the needle points, and means outwardly of the points and separate from the cushion to frictionally grip the needles and hold them against transverse movement.

2. A holder of the character described, comprising in combination a cushion in the holder penetrable by the needle points, and means outwardly of and separate from the cushion provided with pockets spaced apart and adapted to frictionally grip the needles outwardly of the points to secure them against transverse movement.

3. A holder of the character described comprising in combination a pair of disks, means to secure them together in spaced relation, and means to frictionally hold the needles outwardly of their points and against transverse movement in the holder.

4. A holder of the character described, a pair of disks, a cushion between the disks penetrable by the needle points, means to secure them together in spaced relation, and

means outwardly of the cushion adapted to frictionally grip the needles and hold them in radial position.

5. In a device of the character described, the combination of a holder comprising a pair of elements adapted to receive a series of needles in spaced relation between them, and a spring ring between said elements provided with recesses for the needles.

6. In a device of the character described, the combination of a holder comprising a pair of elements adapted to receive a series of needles in spaced relation between them, a spring ring between said elements provided with recesses for the needles, and a cushion for the needle points inwardly of said ring.

7. In a device of the character described, the combination of a pair of disks secured together and provided with marginal radially extending pockets adapted to receive the needles in spaced relation and to frictionally retain them in radial positions and against transverse movement.

8. In a device of the character described, the combination of a pair of disks secured together and provided with marginal radially extending pockets adapted to receive the needles in spaced relation and to frictionally retain them in radial positions and against transverse movement, and a cushion inwardly of the margins and adapted to receive the needle points.

CHARLES O. FOEDISCH.
ROY J. FOEDISCH.
